UNITED STATES PATENT OFFICE.

RICHARD G. DAVIS, OF LAWRENCE, MASSACHUSETTS.

DESIGN FOR A SADDLETREE.

SPECIFICATION forming part of Design No. 34,722, dated July 2, 1901.

Application filed May 22, 1901. Serial No. 61,462. Term of patent 14 years.

To all whom it may concern:

Be it known that I, RICHARD G. DAVIS, a citizen of the United States, and a resident of Lawrence, in the county of Essex and State of Massachusetts, have invented and produced a new and original Design for Saddletrees, of which the following is a specification.

In the accompanying drawings, forming part of this specification, Figure 1 is a plan view of a saddletree, showing my design; and Fig. 2 is a side view thereof.

As shown in the drawings, the leading and material feature of my design consists of a curved saddletree 1, having four flat flanges or projections 2, 3, 4, and 5, which extend from each side of the tree, near the ends thereof. The outer ends of said flanges are rounded, and the contour of their sides merges into the sides of the main part of the tree.

Said flanges are of the same thickness as the adjacent part of the tree on which they are formed and are continuous therewith. Their edges are beveled, as indicated in the drawings. Loops 6 and 7 are provided at the ends of the tree, and a loop 8 is provided midway and at one side thereof.

Having described my invention, what I claim as new, and desire to secure by Letters Patent, is—

The design for a saddletree, as herein shown and described.

In testimony whereof I have affixed my signature in presence of two witnesses.

RICHARD G. DAVIS.

Witnesses:

LOUIS H. HARRIMAN,
G. E. UCKER.
